YOUNGER, ASSIGNOR TO SAID PHILIP T. JACKSON.

HEATING APPARATUS.

1,093,103.

Specification of Letters Patent. Patented Apr. 14, 1914.

Application filed October 23, 1911. Serial No. 656,230.

To all whom it may concern:

Be it known that we, MAUNSELL B. JACKSON, the younger, of the city of Vancouver, in the Province of British Columbia, Canada, and PHILIP T. JACKSON, of the city of Toronto, in the Province of Ontario, Canada, have invented new and useful Improvements in Heating Apparatus, of which the following is a specification.

10 This invention relates to apparatus for heating air for use in heating buildings or for other purposes and particularly to apparatus especially adapted to burn a gaseous or liquid fuel, and our object is to devise 15 a construction which, while simple and comparatively cheap, will enable the heat value of the fuel to be used to the greatest possible advantage.

We attain our object by means of a construction which may be briefly described as follows: Within a suitable casing forming a chamber is located a radiator of substantially an inverted U-shape, the products of combustion from the source of heat passing 25 up one leg and down the other. The chamber is divided by a wall preferably of insulating material and, located between the legs of the radiator, into two separate air passages preferably though not necessarily 30 substantially vertical. A cold air chamber is formed at the bottom of the heater and a hot air mixing chamber at the top of the heater, each communicating with the air passages. The air entering the lower chamber 35 is divided into two independent streams flowing up the air passages and commingling in the mixing chamber. It follows from this construction that the products of combustion pass away from the apparatus at 40 the point where the temperature of the air to be heated is lowest a condition necessary to economy of operation.

The drawings illustrate an embodiment of our invention particularly adapted for 45 an auxiliary house heating plant using gas as fuel but it will be understood, of course, that the invention without change of principle is adaptable for use with any kind of fuel and for any duty involving the absorption of heat from the products of combustion.

Figure 1 is a vertical section of our improved heater. Fig. 2 is a vertical section on the line $a-b$, Fig. 1. Fig. 3 is a plan

view. Fig. 4 is a section on the line $c-d$, 55 Fig. 1. Fig. 5 is a perspective detail of a portion of the down draft leg of the radiator, partly broken away, showing the annular baffles. Fig. 6 is a detail of a modification of the baffles shown in Fig. 5. 60

In the drawings like letters of reference indicate corresponding parts in the different figures.

A is the casing of the heater within which is located a radiator of substantial inverted U-shape, comprising a leg forming the up draft flue B and a leg forming the down draft flue C connected at the top by the cross flue D. The casing is divided by the wall E into two vertical independent air 70 passages G and H respectively surrounding the two legs of the radiator.

At the bottom of the casing is formed the cold air chamber F communicating with the lower ends of the air passages G and H. With this chamber communicates the cold air pipe I. At the upper end of the casing is formed the mixing chamber J into which the air passages G and H open.

In the lower end of the up draft flue is 80 located a suitable heating device, preferably a fluid burner K, adapted to burn gaseous or liquid fuel. With the lower end of the down draft flue C is connected the smoke exit pipe L.

The down draft flue C in order to obtain increased heating surface is preferably annular in shape, being provided with an inner tube M opened at the top and bottom to form a third air passage. 90

The lower end of the annular down draft flue C is formed as a drip trough c to catch water of condensation which may collect in the flue. A pipe b leads from this drip trough to a water pan N located in the 95 chamber F preferably adjacent the burner K.

To obtain a large heating service the flue B is made somewhat larger than is necessary for the passage of the products of combustion and a series of baffles c and d are 100 placed therein preferably alternately circular and annular, insuring that the stream lines of the products of combustion will be thoroughly broken up and all parts of the gases brought in contact with the sides of 105 the flue.

To increase the heating effect of the annular flue C we prefer to place therein a series

of annular metal gratings or baffles *e* which may be of any suitable construction, but are preferably formed of annular troughs of wire netting pressed up into shape and forced down between the walls of the flue to their places. Spacers *f* secured to each grating or baffle and resting on the next lower baffle serve to accurately position these baffles. (See Fig. 5.)

10 As an alternative the baffles *e'* may be made of sheet metal having a series of tongues *f'* stamped therein and bent down at an angle to form the necessary openings, the baffles also being stamped up at each 15 edge to form rings *g'* to engage the walls of the flue. (See Fig. 6.)

To prevent damage due to explosion occurring within the heater we provide relief doors *O* wherever they may be needed. 20 These are hinged by their upper edges so as to swing vertically and are preferably inclined so that the action of gravity normally and yieldingly holds them closed. We show two doors arranged one at each 25 end of the cross flue *D* and closing suitable openings therein, a similar door closing an opening at the lower end of the up flue *B* serving also to give access to the burner and a similar door at the lower end of the smoke 30 exit pipe *L*.

The mode of operation of the heater is as follows: The gaseous products of combustion from the burner which usually include water vapor pass through the up flue 35 *B* losing heat through the walls thereof. At the top of the flue the temperature of the flue gases is still too high for condensation to take place, so that no condensation takes place above the burner. The gases then pass 40 to the cross flue *D* and down the annular, down draft flue *C* giving up heat to the air column on the outside of the outer tube and the air column on the inside of the inner tube, part of their heat being taken up by 45 the gratings and conducted to the walls of the flue to be taken up in turn by the moving streams of air. The temperature of the flue gases in the down draft flue is sufficiently reduced to allow condensation of the 50 water vapor to take place. The water of condensation runs down into the drip trough *a* thence passing to the water pan *N* through the pipe *b*. The water in the pan is evaporated into and carried up by the air passing 55 through the heater. The water pan is preferably made to slide on suitable guides such as the flanges *g* formed at the lower end of the flue *B* so that by adjusting its distance from the source of heat the amount of evaporation can be controlled. If the condensation 60 does not provide sufficient water to moisten the heated air water from some other source can easily be introduced into the pan. It will be seen that the air to be heated enters at the bottom of the heater 65

through the chamber *F* and divides into three columns, one passing up around the up draft flue *B*, one up outside the down draft flue *C* and the other up through the central tube of the down draft flue *C*. The column 70 of air passing up around the up draft flue *B* strikes the walls of the latter at the hottest point in the heater and passes upward in the same direction as the flue gases, the transfer of heat from the gases to the flue 75 taking place at the maximum difference of temperature. The other columns of air come in contact with the down draft flue *C* at a point where the gases leave it and escape to the chimney, the air then traveling 80 upward in the opposite direction to the gases in the flue. It will be seen that the gases leave the heater at the point of lowest temperature, and therefore carry off the smallest possible amount of heat. The columns 85 of heated air join in the mixing chamber *J* and pass out through the pipe *P*. The lower end of the up-draft flue *B* opens directly into the cold air chamber *F* so that the air for combustion is drawn from the 90 cold air supply and not from the room in which the heater is located. This arrangement prevents the dust from the room entering the heater and also utilizes the downwardly radiated heat which is taken up by 95 the air passing through the cold air chamber instead of being wasted.

We consider it of great importance to maintain complete separation between the air passing up in contact with the up draft 100 flue and the air passing up in contact with the down draft flue, since the greatest efficiency is obtained by having the greatest possible difference of temperature between the air to be heated and the walls with which 105 it comes in contact and by arranging the apparatus so that the temperature of the flue gases at their point of exit will be as low as possible compatible with sufficient draft. The wall *E* is, therefore, preferably made of 110 some heat insulating material to prevent the transfer of heat from one side of the heater to the other.

What we claim as our invention is:—

1. In a heater the combination of a casing; a radiator provided with a long up-draft and a long down-draft flue connected at the top by a short transverse flue; a wall dividing the casing into two separated, unobstructed up-draft air passages in one of which is located the up-draft flue and in the other the down-draft flue; a cold air chamber at the bottom of the heater common to both air passages; and a mixing chamber at the top of the heater in which said transverse 125 flue is located and into which said separate air passages discharge.

2. In a heater the combination of a casing; a radiator provided with a long up-draft and a long down-draft flue connected 130.

- at the top by a short transverse flue; a wall dividing the casing into separated, unobstructed up-draft air passages in one of which is located the up-draft flue and in the other the down-draft flue; a cold air chamber at the bottom of the heater common to both air passages; and a mixing chamber at the top of the heater in which said transverse flue is located and into which said separate air passages discharge; a burner located at the lower end of the up-draft flue; and baffles located in both the up-draft and down-draft flues.
3. In a heater the combination of a casing; a radiator provided with a long up-draft and a long down-draft flue connected at the top by a short transverse flue; a wall dividing the casing into two separated, unobstructed up-draft air passages in one of which is located the up-draft flue and in the other the down-draft flue; a cold air chamber at the bottom of the heater common to both air passages; a mixing chamber at the top of the heater in which said transverse flue is located and into which said separate air passages discharge; and a smoke exit flue connected with the down-draft flue and extending through the cold air chamber to the outside of the apparatus.
4. In a heater the combination of a radiator provided with an up-draft and a down-draft flue; separate air passages surrounding said flues; means for admitting air at the bottom of each passage; a mixing chamber at the top of the heater into which said separate air passages discharge; a fluid burner in the lower end of the up-draft flue; a smoke exit pipe connected with the down-draft flue near its lower end; a drip trough at the lower end of the down-draft flue; a water pan outside the lower end of the up-draft flue; and a pipe leading from the drip trough to the water pan.
5. In a heater the combination of an up-draft flue; a down-draft flue; a drip trough at the lower end of the down-draft flue; a water pan outside the lower end of the up-draft flue; and a pipe leading from the drip trough to the water pan.
6. In a heater the combination of a burner adapted to use a fluid fuel; an up-flue and a down-flue for the passage of the products of combustion; air passages about said flues; means for collecting water of condensation in said flues located at the bottom of the down-flue; means for evaporating the water of condensation to moisten the air passing through said passages and a conduit leading from the collecting means to the evaporating means.
7. In a heater the combination of a burner adapted to use fluid fuel; flues for the passage of the products of combustion; air passages about said flues; a water pan for collecting water of condensation located in one of said flues where the temperature is relatively low; and an evaporating device in the air space of the heater with which said pan communicates, so that the water of condensation is evaporated to moisten the air passing through the aforesaid passages.
8. In a heater the combination of a casing; a radiator provided with an up-draft and a down-draft flue; a wall dividing the casing into two up-draft air passages in one of which is located the up-draft flue and in the other the down-draft flue; a cold air chamber at the bottom of the heater communicating with both the air passages and with the lower end of the up-draft flue; and a mixing chamber at the top of the heater into which said separate air passages discharge.
9. In a heater the combination of a casing; a radiator provided with an up-draft and a down-draft flue; a wall dividing the casing into two up-draft air passages in one of which is located the up-draft flue and in the other the down-draft flue; a cold air chamber at the bottom of the heater communicating with both the air passages and with the lower end of the up-draft flue; a mixing chamber at the top of the heater into which said separate air passages discharge; and a burner located at the lower end of the up-draft flue.
10. In a heater the combination of a casing; a radiator provided with an up-draft and a down-draft flue; a wall dividing the casing into two air passages in one of which is located the up-draft flue and in the other the down-draft flue; a cold air chamber at the bottom of the heater communicating with both the air passages and with the lower end of the up-draft flue; and a mixing chamber at the top of the heater into which said separate air passages discharge and an inner tube in one of the flues forming an air passage extending from the cold air chamber to the mixing chamber.
11. In a heater the combination of a casing; a radiator provided with an up-draft and a down-draft flue; a wall dividing the casing into two air passages in one of which is located the up-draft flue and in the other the down-draft flue; a cold air chamber at the bottom of the heater communicating with both the air passages and with the lower end of the up-draft flue; a mixing chamber at the top of the heater into which said separate air passages discharge; and a burner located at the lower end of the up-draft flue, the cold air chamber having its inlet adjacent the lower end of the down-draft flue.
12. In a heater the combination of a casing; a radiator provided with an up-draft and a down-draft flue; a wall dividing the casing into two air passages in one of which is located the up-draft flue and in the other

the down-draft flue; a cold air chamber at the bottom of the heater communicating with both the air passages and with the lower end of the up-draft flue; a mixing chamber at the top of the heater into which said separate air passages discharge; a burner located at the lower end of the up-draft flue and a door closed passage communicating with the up-draft flue above the burner and extending outside of the apparatus.
